UNITED STATES PATENT OFFICE.

GARRY J. DORMANDY, OF TROY, NEW YORK.

FOLDING-MACHINE.

1,216,293.

Specification of Letters Patent. Patented Feb. 20, 1917.

Application filed December 4, 1911. Serial No. 363,810.

To all whom it may concern:

Be it known that I, GARRY J. DORMANDY, a citizen of the United States, residing at Troy, Rensselaer county, New York, have 5 invented certain new and useful Improvements in Folding-Machines, of which the following is a specification.

My invention relates to machines for folding and pressing blanks for collars, cuffs, 10 and like articles. Its object is to infold the edges of such blanks smoothly and correctly, to press the infolded edges after the folding operation so that they will perfectly maintain their folds, and to place the folded and pressed blanks in superposed position 15 ready for removal from the machine. Further objects of the invention, as well as the means for effecting such objects, will appear in this specification and be pointed 20 out in the claims.

In the drawings, Figure 1 is a front, Fig. 2, a rear, and Fig. 3 a right end elevation of a preferred embodiment of my invention, which I have selected for illustration; Fig. 25 4 is a vertical section through the plane 4—4, Fig. 1; Fig. 5 is a partial vertical section through plane 5—5, Fig. 2; Fig. 6 is a similar view through plane 6—6, Fig. 1; Figs. 7 to 14 illustrate details of the invention, as 30 will be hereafter explained.

11 designates the main frame or standard of the machine, provided at its right end with bearings 12 for shaft 13; on which is keyed coupling member 14, adapted to clutch 35 with loose pulley 15, which may be continuously driven by suitable means, as a belt, not shown, see Fig. 3. A pedal 16 is pivoted at 17 in floor brackets 18 and carries a rigid arm 19 pivotally connected by bar 40 20 to arm 21, the upper end of which is keyed on a short rock shaft 22, to which is secured forked arm 23 connected by pins 24 to the collar portion of clutch member 14. A spring 25 acts through parts 19 to 24 to 45 normally hold clutch members 14, 15 in operative relation. A shaft 26 carries disks 27, Figs. 2 and 5, on one (or both) of which is a roller pin 28 bearing against lever 29, which is connected by link 30 and pull spring 31 to arm 21, whereby each rotation of shaft 26 acts to uncouple clutch members 14, 15 and stop the machine. On fore and aft shaft 13 is a worm gear 32 driving cog-wheel 33 on shaft 34, on which is fast cam 50 wheel 35, the face of which is formed with a cam slot 36, in which rides a pin 37 pro-

jecting laterally from arm 38, the other end of which is fast to a hollow rockshaft 39, to which shaft is also clamped a plurality of arms 40, which pass upward through suitable apertures in bedplate 11^a of the machine, and have pin and slot connection with front folder bar 41, to which is detachably secured front folder blade 42. A second cam wheel 43 is also fast on shaft 34 and acts 60 through arm 44 to rock shaft 45, on which are clamped, as before, arms 46 connected to rear folder bar 47, carrying folder blade 48, see Fig. 4. Near each end of shaft 34 is secured a cam wheel 49 having a peripheral cam 65 groove 50, which acts through levers 51, 52, each fast on a rock shaft 53, to move end folder bars 54 and their attached blades 55, see Figs. 2 and 3. Meshing with gear wheel 34^a is a gear wheel 56 on shaft 26, which 70 shaft carries cam wheel 57 having face cam groove 58 in which moves pin 59 in arm body 60, the lower end 61 of which is forked for free vertical movement on shaft 26. A head portion 62 is connected to body part 80 60 by right and left threaded rod 63, head 62 being forked to engage lever 64 pivoted at 65 to a pair of ears 66 on frame 11. To lever 64 is secured a V-shaped carrier 67 having a depending portion 68 to which is adjustably bolted a supporting bar 69 for a templet blade 70. As shown bar 69 and blade 70 are divided into separate parts in the usual manner. In addition, one end of bar 69 carries a part 71 pivoted at 72 and 85 having a blade 73, which forms one end of templet 70, and is normally held in a plane therewith by spring 74, part 71 being notched at 75, to permit the downward movement of blade 73, Figs. 1 and 4. On 90 shaft 34 is a cam wheel 76 having on its face a cam groove 77 in which rides pin 78 on arm 79 which is fast on rock shaft 80. On shaft 80 are two inverted saddles 81, each having a notch 82 freely embracing 95 shaft 80 and formed with a transverse recess 83 in which engages pin 84 on the shaft.

Pivoted to and rising from each end of each part 81 is a bolt 85, which bolts pass through slots in bed 11^a and folder bars 41, 47. At the top of each bolt is a nut 86 between which and the upper surface of the folder bar is a spring 87, Figs. 4 and 6. A steam chest 88 beneath the front portion of bed 11^a is fed by pipe 89 and extends forwardly to an angularly disposed front wall 90. On shaft 34 is a cam wheel 91, Fig. 7,

having cam groove 92 in which moves pin 93 on arm 94, which acts to rock shaft 95 at the ends of which are arms 96, Figs. 1 and 3, pivoted at 97 to arms 98, having right and 5 left threaded adjusting rods 99, to rock shaft 100. Shaft 100 is journaled in bearings 101 which slide in ways 102 and carries a swiveled casting 103, having a plane rear face 104, the lower edge of the casting being 10 normally drawn forward by springs 105, Figs. 3 and 4. Also mounted on shaft 100 at the ends of casting 103 are ears 106 having upper and lower rearward projections 107, on which are pivoted pressing plates 108 of 15 L-shaped cross-section, Figs. 4, 6 and 7, normally held by springs 109 in the angular position shown in Fig. 7. Mounted at the left end of shaft 34, Figs. 1 and 8, is a cam wheel 110 having in its inner face cam 20 groove 111, in which moves pin 112 on arm 113, which acts to rock shaft 114 carrying two pairs of pivoted arms 115, 116, Figs. 4 and 10, for reciprocating a longitudinal bar 117 mounted at the rear of an inclined bed 25 118. Bar 117 carries a plurality of blades or fingers 119 located beneath and normally slightly to the rear of the front wall 90 of steam chest 88. The outer face of cam wheel 110 has a cam groove 120, in which rides 30 pin 121 on arm 122 which rocks shaft 123, on which are two forked arms 124 embracing bar 125, Figs. 3, 8 and 9, from which extends upwardly a second series of blades or fingers 126, which pass through slots in bed 35 118 in front of the normal position of blades 119. In the periphery of wheel 110 at its inner side is a cam depression 127 coacting with roller 128 on lever 129, which lever has pin and slot connection at 130, Figs. 1, 40 9, 10 and 11, with bar 131 beneath bed 118 for reciprocating the bar longitudinally of the bed. A transverse blade 132 is fast at the end of bar 131 so as to move above bed 118. A pull spring 133 attached to bar 45 131 acts to hold roller 128 against the periphery of wheel 110. A blade 134, similar to 132, is secured to bar 135 at the opposite end of bed 118, which bar is moved with bar 131, but in an opposite direction, by means 50 of two small gears 136 and pin and slot connections 137 beneath bed 118. On bed 118 are two transverse undercut guide bars 138 which serve to detachably engage a "buncher" or device for receiving and 55 removing a number of blanks after they have been operated upon by the machine. This device 139 consists of two U-shaped end pieces 140, the bases of which have dovetailed extensions 141 to engage under guides 60 138, the rear upturned ends forming fingers 142, which when the device is in place are in a plane with the rear blades 119 above described, and the front upturned ends 143 being pierced for the free passage of rods 144, the rear ends of which are secured to a board 65

145, normally forced rearwardly by springs 146 on the rods 144, the end pieces 140 being secured to a longitudinal bar 147.

Premising that the particular machine illustrated is set up for infolding blanks for collar bands or tops, the length of which is much greater than their width, and that these blanks ordinarily consist of two superposed plies, the operation of the machine is as follows: The operator places a blank on 75 bed 11^a of the machine in the space beneath templet 70, Fig. 4. He then starts the machine by tilting pedal 16, which acts through parts 19 to 24, Fig. 5, to engage clutch member 14 with constantly driven pulley member 80 15. Templet 70 is then forced down on bed 11^a, or rather on the blank laid thereon, by the action of cam wheel 57, Fig. 4, and dwells there while pin 59 travels around the concentric portion of cam groove 58. During 85 this dwell of the templet, end infolder blades 55, actuated by cams 49 and connecting parts 51 to 54, Figs. 2 and 3 act to fold the end edges of the blank over the ends of templet 70; after which front and rear folder blades 90 42 and 48, moved by cams 35 and 43 and connecting parts, Fig. 4, infold the long edges of the blank.

After the folding operation is thus completed, cam 76, Fig. 6, acts through parts 95 78 to 87 to force the folding blades, still in their inward position, down upon the edges of the folded blank to set or preliminarily press the folds over the periphery of the templet, the pressure of the blades being 100 regulated by nuts 86 acting through springs 87. This pressure being withdrawn by the passing of pin 78 into the outer concentric portion of groove 77, Fig. 6, the further rotation of shaft 34 acts to retract all four infolder blades and afterward to raise templet 70 to its highest position, Fig. 3, at which time pin 28 bears against lever 29, see also Fig. 5, withdraws clutch member 14 from engagement with member 15 and stops 110 the machine. Broadly speaking, these operations of infolding the edges of the blank and of setting the folds by a downward movement of the infolders are well known in the art. 115

But in practice, the folded edges of the blank are found to be inadequately pressed by this fold-setting operation, so that they will not maintain a close, smooth fold during the later handling. This is particularly true where the machine is run at speed, whereby the time of the dwell of the infolders is very short. 120

I have therefore provided means, the operation of which I will now describe, for 125 thoroughly pressing the folded blanks.

The machine having been stopped as above described with the templet in its raised position, the folded blank being still on the templet and being raised therewith, 130

the operator first places a second, unfolded, blank on bed 11^a, and then removes the folded blank from the templet. To do this, he takes hold of the right end of the blank, 5 depresses the part 71 of the templet to the position shown in dotted lines, Fig. 1, which shortens the templet, slips the blank slightly to the left and takes it off the templet without seriously disturbing its folds. 10 Holding this folded blank in his hands, he starts the machine by tilting pedal 16 as before. During this latter part of the first cycle of the machine, including the time when the rotation of shaft 34, by which all 15 parts of the machine are driven, is arrested, pressing plates or shutters 108 have been held in parallel relation with and closely against pressing bed 90, Figs. 3 and 4. When the machine starts, pin 93 passes out 20 of the outer concentric position of groove 92 to the position shown in Fig. 7, *i. e.*, its position nearest to the axis of cam 91, whereby plates 108 are moved to their greatest 25 distance from bed 90, leaving a clear space between the plates and the bed even at the lower edge of the lower plate. A further partial rotation of cam 91 brings pin 93 into the inner circumferential portion 92^a of groove 92, which moves plates 108, still in 30 angular relation with each other, slightly inward so that the lower edge of the lower plate substantially touches bed 90, Fig. 6. The operator then drops the folded blank 35 into the space or pocket thus formed between bed 90 and plates 108. As pin 93 passes through the straight portion 92^b of groove 92, plates 108 are forced toward bed 90, their outer edges first approaching and 40 contacting with the bed, Fig. 13, plate 104 finally acting to bring them into the same plane and to force them against bed 90, or more properly, against the folded blank which has been dropped into the pocket, as 45 just described, Figs. 3 and 4. Thus the folded edges of blank B, Fig. 13, if at any part of their length they are slightly up-standing as shown, will be forced inward to 50 their proper position before the pressure is applied.

If these hinged plates were omitted, and a flat plate, as 104, were forced directly against bed 90, there would be a tendency to crush these upturned edges, instead of ironing them down smoothly upon the surface of the blank. After the machine starts 55 in its next cycle, *i. e.*, after a second blank has been folded as already described, the plates again assume the position shown in Fig. 7, and the lower plate 108 is removed 60 a second time from bed 90 so that the folded and perfectly pressed blank is free to drop from the pocket into the space between the longitudinal series of fingers 119 and 126, Figs. 7 and 11.

As the rear upturned fingers 142 of

buncher 140, Figs. 3 and 11, are in a plane with fingers 119, and as board 145 of the buncher is held forward against the action of springs 146 by front fingers 126, the blank is also between fingers 142 and board 70 145 of the buncher and is supported by its lower edge resting on transverse bars 140 thereof. After the blank has dropped into this space, roller 128 passes into depression 127 in wheel 110, Figs. 1 and 2, when spring 75 133 pulls lever 129, thereby forcing inward blades 132, 134, Figs. 9 and 11, through the action of bars 131, 135 and gear connections 136, 137.

These blades are so adjusted on their respective carrying bars 131, 135 that the minimum distance between them is equal to the length of the blank, whereby one or the other pushes against an end of the blank, if it is at all displaced longitudinally, and 85 forces it to a central position with respect to the buncher.

During the third and subsequent cycles of the machine, the folded and pressed blanks are released from fingers 119, 126, 90 leaving them in superposition on buncher 139, as follows: While the pressing operation is going on, Figs. 3, 4 and 8, cam groove 111 in wheel 110, Fig. 8, acts through pin 112, arm 113, rock shaft 114, links 115, 116, 95 and bar 117 to force forward rear fingers 119 from their blank receiving position, Figs. 3 and 4, to a position slightly in front of fingers 126, Fig. 8. While they remain in this position, *i. e.*, while pin 112 passes 100 through the inner circumferential dwell 111^a in groove 111, pin 121 passes into the eccentric portion of groove 120 in the outer face of wheel 110, and acts, through arm 122, shaft 123, forked arm 124 and bar 125, 105 to lower fingers 126 to their dotted line position, Fig. 8, with their upper ends flush with or slightly below the surface of bed 118. Further rotation of wheel 110 returns fingers 126 to their upward position, shown 110 in solid lines, Fig. 8, but behind the blank, which is meantime pushed forward by fingers 119, which then withdraw to their normal, rearward position. It will be seen that both sets of fingers 119 and 126, as 115 well as fingers 142 of buncher 139 are now at the rear of the blank, which is resiliently held back against fingers 126 by the spring pressed board 145. Obviously, the following cycles of the machine will place successive blanks, one behind the other, on buncher 120 139 in the same manner, the buncher being withdrawable from the bed 118 at any time by sliding it out from engagement with guide bars 138.

It will be understood that very many mechanical alterations may be made in the various parts of the machine without departing from my invention, and that certain parts of the machine perform their function 130

independently of the particular construction of other parts. Thus, *e. g.*, the infolding means, the means for preliminarily pressing or "setting" the folds, the final or actual 5 pressing device, the means for handling the pressed blanks and the removable buncher or carrier, do their work, each to a greater or less extent independently of the form or action of the others. As previously 10 stated, however, the operations of these different elements are interdependent or coöperative with respect to each other by reason of their mutual connection to a single operating part, drive shaft 34, by which they are 15 all driven in the harmonious timed relation set forth; so that all the blank folding operations and that of setting the folds on folding bed 11^a are carried on, after the machine is in full operation, simultaneously 20 with the operation of finally pressing a folded blank on bed 90, and with that of receiving and positioning a pressed blank.

It is understood that the blanks to be folded in a machine of this character are 25 first moistened, and that the pressing operation requires a definite time for removing this moisture and firmly setting the folds. A relatively considerable time is also consumed in removing a folded blank from the 30 folding means and replacing it by a second blank, even where, as in the present form of construction, the folded blank is raised from the bed by the templet, and even where, as also shown herein, the machine is stopped 35 for this purpose. An important feature of my invention, therefore, lies in so constructing and timing the machine that the final pressing means is in operation during this time when the blank is being removed and 40 replaced, whereby the capacity of the machine is greatly increased.

Another very important feature of my invention resides in the fact that each blank is pressed directly after its removal from 45 the folding mechanism and during the next following cycle of the machine. The blank tends to dry out quite rapidly, this being especially the case where it is given a preliminary setting after the folding operation and 50 before its removal from the templet, so that it is essential that the pressing, or final pressing, operation take place with the least possible loss of time.

What I claim is:

- 55 1. In a machine for folding and pressing the folded edges of blanks of textile material, folding means including a bed, a templet and infolders adapted to infold the entire periphery of the blank; means for 60 pressing the folded edges of the blank after it has been removed from said folding means, said pressing means including a second bed, two pressing plates normally maintained in different planes and means for forcing said plates into parallel relation with said last- 65 plates into parallel relation with said last-

named bed during their approach thereto; and means for simultaneously actuating said folding and said pressing means, substantially for the purposes set forth.

2. In a machine for folding and pressing 70 the folded edges of blanks of textile material, folding means including a bed, a templet movable toward and from said bed and infolders; means for pressing the folded edges of the blank after it has been removed from said templet, said pressing means including a second bed, two pressing plates normally maintained in different planes and means for forcing said plates into parallel relation with said last-named 75 bed during their approach thereto; and means for simultaneously actuating said folding and said pressing means, substantially for the purposes set forth.

3. In a machine for folding and pressing 80 the folded edges of blanks of textile material the length of which is greater than their width, folding means including a bed, a templet and a series of infolders adapted to infold the entire periphery of the blank; 85 means for preliminarily pressing the folded edges of the blank during its contact with said bed; means for finally pressing the folded edges of the blank after it has been removed from said folding means, said final 90 pressing means including a second bed, two pressing plates normally maintained in different planes and means for forcing said plates into parallel relation with said last-named bed during their approach thereto; 95 and means for simultaneously actuating said folding and both said pressing means, substantially for the purposes set forth.

4. In a machine for folding and pressing 100 the folded edges of blanks of textile material, folding means including a bed, a templet movable toward and from said bed and infolders; means for preliminarily pressing the folded edges of the blank before its removal from said templet; means for finally 110 pressing the folded edges of the blank after it has been removed from said templet, said final pressing means including a second bed, two pressing plates normally maintained in different planes and means for forcing said plates into parallel relation with said last-named bed during their approach thereto; 115 and means for simultaneously actuating said folding and both said pressing means, substantially for the purposes set forth.

5. In a machine for folding and pressing the folded edges of blanks of textile material the length of which is greater than their width, folding means including a bed, a templet having a part movable with respect to another part for facilitating the removal of the blank therefrom and a series of infolders adapted to infold the edges of the blank around the entire periphery of said templet; 125 means for preliminarily pressing the folded 130

edges of the blank before its removal from said templet; means for finally pressing the folded edges of the blank after it has been removed from said templet, said final pressing means including a second bed, two pressing plates normally maintained in different planes and means for forcing said plates into parallel relation with said last-named bed during their approach thereto; and means for simultaneously actuating said folding and both said pressing means, substantially for the purposes set forth.

6. In a folding machine, a single stationary heated chamber having two independent bed surfaces; means including one of said surfaces for infolding the entire periphery of a blank; and means, including the other of said surfaces, two pressing plates normally maintained in different planes and means for forcing said plates into parallel relation with said last-named surface during their approach thereto, for finally pressing the folded edges of the blank.

7. In a folding machine, means for pressing the folded edges of a blank including two co-acting bodies one of which is movable toward the other and one of which consists of two relatively movable parts in juxtaposition to each other and adapted to cover substantially the entire blank; means for maintaining the surfaces of said parts with their proximate edges farther removed than are their outer edges from the surface of the other body during their approach thereto; and means for forcing said parts into parallel relation with the surface of said other body during the pressing operation.

8. In a folding machine, fold pressing means including a heated bed and a co-acting pressing plate comprising two relatively movable parts in juxtaposition to each other and adapted to cover substantially the entire blank; means for moving said plate toward and from said bed; and means for maintaining one of said parts in angular relation with said bed during its approach thereto.

9. In a folding machine, fold pressing means including a heated bed and two co-acting pressing plates in juxtaposition to each other and adapted to cover substantially the entire blank; and means for moving said plates toward and from said bed and for maintaining them with their proximate edges farther removed than are their outer edges from said bed during their approach thereto.

10. In a folding machine, fold pressing means including a heated bed and a co-acting pressing plate comprising two relatively movable parts disposed one below the other; means for moving said plate toward said bed in such relation that the lower edge of

the lower of said parts is first brought into substantial contact with said bed, whereby a "pocket" is formed for the reception of a blank, and that both parts of said plate are afterward brought into operative parallel relation with said bed.

11. In a folding machine, means for pressing the folded edges of a blank including a heated bed and a co-acting pressing plate comprising two relatively movable parts in juxtaposition to each other and adapted to cover substantially the entire blank; and mechanically actuated means for moving said plate toward and from said bed so that it successively assumes blank-receiving, pressing and -discharging positions.

12. In a folding machine, means for pressing the folded edges of a succession of blanks, said pressing means being constructed and fitted to permit each blank after pressing to drop therefrom by its own weight; and means positioned beneath said pressing means for receiving such blanks directly therefrom and for retaining them in juxtaposition with each other in a substantially vertical plane.

13. In a folding machine, means, including co-acting pressing surfaces positioned in an approximately vertical plane, for pressing the folded edges of a succession of blanks; means for moving said surfaces apart after each blank is pressed so as to permit such blank to drop therefrom by its own weight; and means positioned beneath said pressing means for receiving such blanks directly therefrom and for retaining them in juxtaposition with each other in a substantially vertical plane.

14. In a folding machine, a heated bed; a part movable toward and from said bed; two pressing plates pivoted on said part one beneath the other; means for holding the lower of said plates with its upper edge farther removed than its lower edge from said bed; and means for moving both said plates in angular relation with each other toward said bed and for afterward forcing them against said bed in the same plane.

15. In a folding machine, a heated bed; a part movable toward and from said bed; two pressing plates pivoted on said part; means for holding said plates with their proximate edges farther removed than their outer edges from said bed; and means for moving said plates in such angular relation with each other toward said bed, and for afterward forcing them against said bed in the same plane.

16. In a folding machine, a heated bed; a part movable toward and from said bed; two pressing plates pivoted on said part; means for holding said plates with their proximate edges farther removed than their outer edges from said bed; and means for moving said plates in such angular relation

with each other toward said bed and so that the outer edge of the lower plate is first brought into substantial contact with said bed, and for afterward forcing them against said bed in the same plane.

5 17. In a folding machine, a heated bed; a transversely movable shaft; a part having slotted connection with said shaft for movement thereon and therewith; two pressing plates pivoted on said part; means for holding the lower of said plates with its upper edge farther removed than its lower edge from said bed; and means on said shaft for moving said plates in angular relation with each other toward said bed and for afterward forcing them against said bed in the same plane.

10 18. In a folding machine, a heated bed; a part movable toward and from said bed; two pressing plates pivoted on said part; springs for holding said plates with their proximate edges farther removed than their outer edges from said bed; and means bearing against the rear faces of said plates for moving them in such angular relation with each other toward said bed and for afterward forcing them against said bed in the same plane.

15 19. In a folding machine, a heated bed; a part movable toward and from said bed; two pressing plates pivoted on said part one beneath the other; means for holding the lower of said plates with its upper edge farther removed than its lower edge from said bed; and means operative on said plates at predetermined intervals, first to move the lower edge of the lower plate into approximate contact with said bed, next to force the faces of said plates against said bed, and finally to remove said plates from said bed.

20 20. In a folding machine, folding means including a bed infolders and a templet movable toward and from said bed; and pressing means independent of and removed from all said folding means and including a bed and a plurality of independently movable portions, said pressing means being operative while said templet is farthest removed from said bed.

25 21. In a folding machine, a bed, infolders; a templet; means for moving said templet toward and from said bed and for holding it in its removed position during a part of the cycle of the machine; a heated pressing bed independent of said first-named bed; a pressing plate co-operating with said pressing bed; and means for holding said pressing parts in operative relation while said templet is held in such removed position.

30 22. In a folding machine, a bed; infolders; a templet movable toward and from said bed; a pressing bed independent of said first-named bed; a pressing plate rela-

tively movable toward and from said pressing bed; means for moving said infolders, templet and one of said pressing parts in timed relation; and means for stopping the machine while said templet is in its removed position and said pressing parts are in operative relation.

35 23. In a folding machine, a bed, infolders; a templet movable toward and from said bed; a pressing bed independent of said first-named bed; a pressing plate movable toward and from said pressing bed; means for moving said infolders, templet and pressing plate in timed relation; and means for stopping the machine while said templet is in its removed position and said pressing plate is forced against said pressing bed.

40 24. In a folding machine, a bed; infolders; a templet movable toward and from said bed; a pressing bed independent of said first-named bed; two bodily and pivotally movable pressing plates; means for holding the lower of said plates with its upper edge farther removed than its lower edge from said pressing bed; means for first moving said plates in angular relation with each other toward said pressing bed and for afterward forcing them against said bed in the same plane; means for moving said infolders, templet and pressing plates in timed relation; and means for holding said templet in its removed position and said pressing plates forced against said pressing bed during a part of the cycle of the machine.

45 25. In a folding machine, a bed; infolders; a templet movable toward and from said bed; a pressing bed independent of said first-named bed; two bodily and pivotally movable pressing plates in normal angular relation with each other and adapted to be forced against said pressing bed in the same plane; means for moving said infolders, templet and pressing plates in timed relation; and means for stopping the machine while said templet is in its removed position and said plates are forced against said pressing bed.

50 26. In a folding machine, blank infolding means including a bed, a templet movable in an approximately vertical direction toward and from said bed and infolders adapted to fold the edges of the blank over the entire periphery of said templet; pressing means including a bed independent of said first-named bed and a plate movable toward and from said last named bed; and a single moving part, as a shaft, connected to said templet to raise and lower it and to hold it in operative relation to said first named bed and in its raised position, to said infolders to move them inwardly over the periphery of said templet and outwardly therefrom, and to said plate to force it against said pressing bed and to hold it in

pressing relation therewith, the connections between said moving part, said templet and said plate being constructed and timed to hold said templet in its raised position and 5 to hold said plate forced against said pressing bed during the same part of the cycle of the machine.

27. In a folding machine, blank infolding means including a bed, a templet movable in an approximately vertical direction toward and from said bed and infolders adapted to move inwardly over the entire periphery of said templet and outwardly therefrom and to be forced downwardly while in their 15 inward position; final pressing means including a pressing bed independent of said first-named bed and a plate movable toward and from said last-named bed; and a single moving part, as a shaft, connected to said 20 templet to raise and lower it and to hold it in operative relation to said first-named bed and in its raised position, to said infolders to move them inwardly and outwardly and to force them downwardly, and 25 to said plate to force it against said pressing bed and to hold it in operative relation therewith, the connections between said moving part, said templet and said plate being constructed and timed to hold said 30 templet in its raised position and to hold said plate forced against said pressing bed during the same part of the cycle of the machine.

28. In a folding machine, blank infolding means including a bed, a templet movable in an approximately vertical direction toward and from said bed and infolders adapted to move inwardly over the edges of said templet and outwardly therefrom; pressing 35 means including a bed independent of said first-named bed and a plate movable toward and from said last-named bed; a single moving part, as a shaft, connected to said templet to raise and lower it and to hold it in its raised position, to said infolders to move them inwardly over the edges of said templet and outwardly therefrom, and to 40 said plate to force it against said pressing bed and to hold it in pressing relation therewith; and means for stopping the machine while said templet is in its raised position and said plate is held in operative pressing 45 position.

29. In a folding machine, blank infolding means including a bed, a templet movable in an approximately vertical direction toward and from said bed and infolders adapted to move inwardly over the edges of said templet and outwardly therefrom and to be 50 forced downwardly while in their inward position; final pressing means including a bed independent of said first-named bed and a plate movable toward and from said last-named bed; a single moving part, as a shaft, connected to said templet to raise and lower it and to hold it in raised position, to said infolders to move them inwardly over the edges of said templet and outwardly therefrom, and to said 55 plates to force them against said pressing bed and to hold them in pressing relation therewith.

30. In a folding machine, means for infolding the edges of a blank; means for stopping the machine after the blank has been folded to permit its removal from said infolding means; and means independent of said folding means for pressing the blank 70 after its removal from said folding means and including a bed and a plurality of independently movable portions, said pressing means being operative during the stoppage of the machine.

31. In a folding machine, means for infolding the edges of a blank; and means independent of said folding means for pressing the blank after its removal from said folding means and including a bed and a 75 plurality of independently movable portions, said pressing means being operative during the time required for removing the blank from said infolding means and for placing a second blank in position for the 80 folding operation.

32. In a folding machine, blank infolding means including a bed on which the blank is laid and a templet operative to raise the blank from said bed after the folding operation; means for holding said templet in its raised position to permit the removal of the folded blank therefrom and the placing of an unfolded blank on said bed; and means independent of said folding means 85 for pressing the folded blank after such removal and including a bed and a plurality of independently movable portions, said pressing means being operative while said templet is in its raised position.

33. In a folding machine, blank infolding means including a bed, a templet movable toward and from said bed and infolders movable inwardly over the edges of said templet and outwardly therefrom; pressing 90 means independent of said folding means including a bed and two pivotally mounted plates normally maintained in angular relation with each other and movable toward and from said pressing bed; and a single 95 moving part, as a shaft, connected to said templet to raise and lower it and to hold it in raised position, to said infolders to move them inwardly over the edges of said templet and outwardly therefrom, and to said plates to force them against said pressing bed and to hold them in pressing relation therewith.

34. In a folding machine, blank infolding means including a bed on which the blank 100

is laid and a templet operative to raise the blank from said bed after the folding operation; means for holding said templet in its raised position to permit the removal of the folded blank therefrom and the placing of an unfolded blank on said bed; means independent of said folding means for pressing the folded blank after such removal and including a bed and a plurality of independently movable portions; and means for stopping the machine while said templet is in its raised position and while said pressing means is in operative relation to the blank.

35. In a folding machine the combination of a folding bed, a folding mechanism for folding blanks on said bed while defined by a templet, a templet for defining the blank folds, said templet adapted and fitted to be lowered upon the bed and raised therefrom, a pressing device independent of said folding mechanism, said device including two approximately vertical pressing parts adapted to receive, close upon and firmly press and crease a folded blank after its disengagement from the templet and to open to permit the pressed blank to drop therefrom by its own weight; and a single operating part, as power shaft 34, having connections to the folding mechanism, the templet and the pressing device for effecting harmonious operations thereof.

36. In a folding machine the combination of a folding bed, a folding mechanism for folding blanks on said bed while defined by a templet, a templet for defining the blank folds, said templet adapted and fitted to be lowered upon the bed and raised therefrom, a pressing device independent of said folding mechanism, said device including two approximately vertical positively operated pressing parts adapted to receive, close upon and firmly press and crease a folded blank after its disengagement from the templet and to open to permit the pressed blank to drop therefrom by its own weight, a receptacle for the blanks beneath said pressing device; and a single operating part, as power shaft 34, having positive connections to the folding mechanism, the templet and the pressing device so constructed and timed that successive blanks may be operated upon simultaneously and in the following order: templet descends to define blank, folding mechanism folds blank, templet rises, presser opens to receive disengaged blank, presser closes to press blank, presser re-opens to permit discharge of pressed blank into said receptacle, the connections between said operating part and one of said pressing parts being constructed and fitted to positively force said last named pressing part toward the other.

37. In a folding machine the combination of a folding bed, a folding mechanism for

folding blanks on said bed while defined by a templet, a templet for defining the blank folds, said templet adapted and fitted to be lowered upon the bed and raised therefrom and to carry the folded blanks upward with it from the bed, a positively operated pressing device independent of said folding mechanism, said device including two pressing parts adapted to receive, close upon and firmly press and crease a folded blank after disengagement thereof from the raised templet and to open and discharge a pressed blank therefrom, a receptacle for the pressed blanks discharged from said pressing device; and a single operating part, as power shaft 34, having positive connections to the folding mechanism, the templet and the pressing device for effecting harmonious operation thereof, the connections between said operating part and one of said pressing parts being constructed and fitted to positively force said last named pressing part toward the other.

38. In a folding machine the combination of a folding bed, a folding mechanism for folding blanks on said bed while defined by a templet, a templet for defining the blank folds, said templet adapted and fitted to be lowered upon the bed and raised therefrom and to carry the folded blank upward with it from the bed, a positively operated pressing device independent of said folding mechanism and including two approximately vertical pressing parts adapted to receive, close upon and firmly press and crease a folded blank after its disengagement from the templet and to open to permit the pressed blank to drop therefrom by its own weight, a receptacle for the blanks beneath said pressing device; and a single operating part, as power shaft 34, having positive connections to the templet, the folding mechanism and the pressing device for effecting harmonious operations thereof the connections between said operating part and one of said pressing parts being constructed and fitted to positively force said last named pressing part toward the other.

39. In a folding machine the combination of a folding bed, a folding mechanism for folding blanks on said bed while defined by a templet, a templet for defining the blank folds, said templet adapted and fitted to be lowered upon the bed and raised therefrom and to carry the folded blanks upward with it from the bed, a positively operated pressing device independent of said folding mechanism including two pressing parts adapted to receive, close upon and firmly press and crease a folded blank after disengagement thereof from the raised templet, a receptacle for the pressed blanks discharged from the pressing device; a single operating part, as power shaft 34, having positive connections to the folding mecha-

nism, the templet and the pressing device for effecting harmonious operations thereof; and automatic means for stopping said operating part while said templet is raised from the bed and while the pressing means is in operative position, the connections between said operating part and one of said pressing parts being constructed and fitted to positively force said last named pressing part toward the other.

40. In a folding machine the combination of a folding bed, to which blanks are successively fed, a folding mechanism for folding a blank on said bed while defined by a templet, a templet for defining the blank folds adapted and fitted to be lowered upon the bed and raised therefrom and to carry the folded blank upward with it from the bed, so that a new blank may be inserted on the bed; a positively operated pressing device independent of the folding mechanism including two pressing parts and adapted to receive, close upon and firmly press and crease a folded blank after disengagement from the raised templet and to open and discharge a pressed blank therefrom, said pressing device being located near the raised templet so that blanks from the templet are readily inserted into the pressing device, a receptacle for the pressed blanks discharged from the pressing device; and a single operating part, as power shaft 34, having positive connections to the folding mechanism, the templet and the pressing device for raising and lowering the templet and operating the folding mechanism in harmonious relation on one blank and simultaneously moving said pressing device to receiving, pressing and discharging positions on a previously folded blank, the connections between said operating part and one of said pressing parts being constructed and fitted to positively force said last named pressing part toward the other.

41. In a folding machine the combination of a folding mechanism for folding the edges of a blank, and a pressing device independent of said folding mechanism and adapted to receive, close upon and firmly press and crease a folded blank and to open for the discharge of a pressed blank therefrom, said pressing device comprising two opposed pressing members, at least one of which includes two parts pivotally mounted so as to assume different angular relations with each other during the cycle of the machine.

42. In a folding machine and in combination, blank-folding and fold-setting means including a bed and blank-folding and fold-setting parts adapted to operate upon a blank on said bed to successively fold the blank and preliminarily fix the fold; and final pressing means independent of said blank-folding and fold-setting means constructed and fitted to act upon each of a

series of blanks directly after it is removed from said folding and fold-setting means and while the next succeeding blank of such series is being operated upon thereby.

43. In a folding machine, blank folding means including a bed, a templet movable toward and from said bed and infolders; pressing means independent and movable independently of said folding means; and a moving part for actuating both said folding and said pressing means and connected thereto so that said pressing means is open to receive each of a series of blanks directly after it is removed from said folding means and so that each blank of such series is being acted upon by said pressing means while the next succeeding blank is being operated upon by said folding means.

44. In a folding machine, blank folding means including a bed, a templet and infolders; means for moving said templet toward and from said bed and for holding it in its removed position; pressing means independent and movable independently of said folding means; and actuating means for moving said infolders, said templet operating means and said pressing means and connected thereto so that said infolders are moved outward, said templet removed from said bed and said pressing means opened in immediate succession, and so that each of a series of blanks is acted upon by said pressing means while the next succeeding blank of such series is being operated upon by said folding means.

45. In a folding machine, blank folding means including a bed, a templet movable toward and from said bed and holdable in its removed position, and infolders; independently movable pressing means; a moving part for actuating both said folding and said pressing means and connected thereto so that said pressing means is opened to receive each of a series of blanks directly after it is removed from said folding means and closed for pressing such blank during the time that the next succeeding blank of such series is being operated upon by said folding means; and means for stopping the machine while said templet is in its removed position and while said pressing means is in operative position.

46. In a folding machine, means for folding the edges of each of a series of blanks; means for stopping the machine at the end of each cycle thereof and after each blank has been folded to permit its removal from said folding means; and independently movable means for pressing each blank directly after its said removal from said folding means and during the time occupied by the folding of the next succeeding blank of the series whereby a blank folded during a given cycle of the machine is pressed during the next succeeding cycle.

47. In a folding machine, means for folding the edges of each of a series of blanks; means for stopping the machine at the end of each cycle thereof and after each blank has been folded to permit its removal from said folding means; independently movable means for pressing each blank directly after its said removal from said folding means and during the time occupied by the folding of the next succeeding blank of the series,

whereby a blank folded during a given cycle of the machine is pressed during the next succeeding cycle; said pressing means being operative during the stoppage of the machine.
